FIRE ALARM SIGNAL OR SIMILAR ARTICLE

Joseph T. Sullivan 2nd, Huntingdon Valley, Pa., assignor
to Standard Fire Alarm and Signal, Inc., Jenkintown,
Pa., a corporation of Pennsylvania

Filed Dec. 4, 1961, Ser. No. 67,785

Term of patent 14 years

(Cl. D72—1)

FIG. 1.

FIG. 2.

FIG. 3.

FIG. 4

FIG. 6

FIG. 6

FIG. 1 is a top plan view of a fire alarm signal or similar article showing my new design.

FIG. 2 is a side elevational view thereof.

FIG. 3 is a bottom plan view thereof.

FIG. 4 is a rear elevational view thereof.

FIG. 5 is a front elevational view thereof.

FIG. 6 is a fragmentary perspective view thereof with the horn omitted for convenience of illustration.

I claim:

The ornamental design for a fire alarm signal or similar article, substantially as shown.
